(57) **CLAIM**

The ornamental design for a sticker having a second layer with a machine-readable optical image, as shown and described.

DESCRIPTION

FIG. 1 is a perspective view of a sticker having a second layer with a machine-readable optical image;

FIG. 2 is a top view of the same;

FIG. 3 is a back view of the same;

FIG. 4 is a top view of the sticker with the second layer visible and the top layer perpendicular to the second layer;

FIG. 5 is a perspective view of the same; and,

FIG. 6 is an environmental view of the sticker having a second layer with a machine-readable optical image.

The broken lines shown in the drawings represent portions of the design that form no part of the claimed design.

1 Claim, 6 Drawing Sheets

FIG. 1

FIG. 2

DIRECTIONS

1.

CAREFULLY PEEL BACK THE FRONT COVER.

2.

SCAN THE QR WITH YOUR PHONE AND
RECORD YOUR MESSAGE.

3.

PLACE THE FRONT COVER BACK TO ITS
ORIGINAL POSITION.

4.

REMOVE THIS ADHESIVE SIDE AND STICK
THE CARD ON YOUR GIFT.
